UNITED STATES PATENT OFFICE.

THOMAS J. STURTEVANT, OF WELLESLEY, MASSACHUSETTS, ASSIGNOR TO STURTEVANT MILL COMPANY, OF BOSTON, MASSACHUSETTS, A CORPORATION OF MASSACHUSETTS.

AIR-SEPARATOR.

1,385,846.

Specification of Letters Patent. Patented July 26, 1921.

Application filed October 7, 1919. Serial No. 329,094.

To all whom it may concern:

Be it known that I, THOMAS J. STURTEVANT, a citizen of the United States, residing at Wellesley, in the county of Norfolk and State of Massachusetts, have invented an Improvement in Air-Separators, of which the following description, in connection with the accompanying drawings, is a specification, like characters on the drawings representing like parts.

The invention to be hereinafter described relates to air separators, and more particularly to separators of the type disclosed in my copending applications Serial No. 297,291, filed May 15, 1919, and Serial No. 319,646, filed August 25, 1919.

This type of separator comprises outer and inner casings forming inner and outer chambers and provided with a fan for producing a circulating air current which moves upward in the inner chamber and downward in the outer chamber. The materials to be graded are introduced into the inner chamber through the top thereof and strike a rotary distributor which under the influence of centrifugal force throws the materials outward into the path of the rising current of air. Lighter particles are lifted thereby up to the fan, pass through the fan, and thence downward through the outer chamber, whereas, the heavier particles gravitate downward through the rising current of air in the inner chamber. The fine particles are discharged through one passage, and the coarser particles are discharged through another passage.

In grading of materials, there is a tendency for the lighter particles passing downward through the outer chamber to be carried by the circulating air current back into the inner chamber. If the finer particles are returned to the inner chamber in substantial amount, of course, the efficiency of the separator is materially reduced.

The rotary fan tends to produce a whirling current of air downward through the outer chamber, and the centrifugal force of this air current tends to carry the particles outward against the inner surface of the outer chamber, so that they tend to pass downward past the lower opening between the outer and inner chambers a substantial distance therefrom. The whirl and centrifugal effect diminish as the current ap-

proaches said opening, and the force there- 55 of in some instances is sufficient to give centrifugal effect adequate to prevent entrance of particles back into the inner chamber. One of the purposes of the present invention, therefore, is to provide simple and 60 efficient means for increasing the whirl effect of the air and thereby increasing the centrifugal force thereof, more effectively to prevent return of the lighter particles from the outer chamber into the inner chamber. 65 In carrying this feature of the invention into practical effect, in the present instance, the fan is inclosed in a chamber and one or more guides or conduits of a spiral or helical character are provided, communicating with the fan chamber and the outer chamber so as to deliver the air current into the outer chamber with a pronounced whirl of the air current creating a centrifugal force opposite the lower opening between the outer and inner chambers sufficient to cause the lighter particles to pass downward along or sufficiently adjacent to the inner surface of the outer wall of the outer chamber to greatly reduce the percentage of particles carried by the air current into the inner chamber. 75

Another purpose of the invention is to provide a valve or gate for each of the air conduits which may not only serve to vary 85 the strength of the air current for classification of materials of varying character, but also may serve to contribute to the direction of the whirling air current delivered from the air conduit or air conduits. 90

In my said application Serial No. 297,291, a series of vanes or valves are provided at the lower opening between the outer and inner chambers which serve to promote a whirl effect of the air and also to vary the 95 strength of the air current for classifying materials of varying character. Another purpose of the present invention is to provide an air conduit or air conduits such as described, which may be so related to the 100 vanes referred to, as to coöperate therewith desirably in the production of the whirling air current. In other words, the air conduit or conduits may be so related to said vanes as to direct the whirling air currents in such a 105 manner as to be received by said vanes and directed by the latter from the outer to the inner chamber.

With the aforesaid and other objects in view, the character of the invention will be best understood by reference to the following description of one good form thereof shown in the accompanying drawings, 5 wherein:

Figure 1 is a vertical section taken on line 1-1 of Fig. 2 through the separator shown herein as embodying the invention;

10 Fig. 2 is a plan of the separator;

Fig. 3 is a perspective view of a portion of the separator; and

15 Fig. 4 is a sectional detail of a latch device for holding the air conduit gate in different positions of adjustment.

Referring to the drawings, the separator shown therein as one good form of the invention, comprises a support, in the present instance, in the form of a ring 1 (Fig. 1) 20 having feet 3 adapted to be secured by bolts 5 to beams 7 or other appropriate supporting means.

Mounted on a flange 9 of the foundation ring is an outer casing 11 for the outer chamber 13, said casing having a base ring 15 provided with an internal flange resting on the foundation ring flange 9 and detachably secured thereto by screw bolts 17. The outer casing has a shell 19, in the present instance 30 of cylindrical form, with its lower edge riveted to the base ring 15 and its upper edge riveted to a top ring 21. A head 23 is secured to the top ring and is provided with eyes 25 adapted to be connected to a suitable 35 tackle which may be used for lifting the outer casing from the foundation ring when desired.

Within and spaced from the outer casing is an inner casing 27 for the inner chamber 40 28 and having an upper conical shell 29 and a lower conical shell 31. The adjacent ends of said shells are secured to rings 33 connected by through bolts 35. These rings are shouldered to receive a circular baffle plate 45 37 which may be made in sections and be made of stronger and more durable material than the upper and lower shells 29 and 31. The construction is such that on release of the through bolts 35, the baffle plate 37 may 50 readily be removed and another substituted therefor.

Encircling the lower conical shell 31 is a cylinder 39 having its upper edge secured to the lower ring 33 and its lower edge secured to a ring 41. Projecting outward from the ring 41 are feet 43 having sockets resting on the upper ends of posts 44 which have their lower ends seated in sockets 45 on brackets 47 projecting radially inward from 60 the foundation ring 1.

A conical casing 49 is secured to and depends from the foundation ring and has a port at the lower end thereof through which the fines are discharged, as more fully herein 65 after described.

To conduct the coarser particles from the inner chamber, a mouth or collar 51 has its lower edge secured to an upstanding flange of an angle ring 53 secured to the inner ends of the brackets 47 referred to. Interposed between said angle ring 53 and said brackets is the outwardly projecting flange of a conical collar 55. Depending from the latter is a conical casing 57 communicating with a spout 59 having a delivery end projecting through the fines discharge casing 49 referred to.

The shells 29 and 31 and the intermediate plate 37 divide the outer casing into a separating chamber and a collecting chamber.

10 The materials to be graded may be introduced into the separator through a hopper 61 secured to the head 23. Projecting downward from the hopper is a feed tube 63 for conducting the materials to the rotary distributor device.

The rotary distributor device, in the present instance, comprises a head 65 having a table 67 with vanes 69 rising from a peripheral portion thereof and surmounted by a ring 71. Depending from the edge of said table is an apron 73, and rising from and secured to the ring 71 is a sleeve 75 encircling and spaced from the feed tube 63. An annular dish 77 embraces the apron 73 and has an upstanding flange 79. At the inner end of said dish is a ring 81 connected by vertical posts 83 with a ring 85. A tapered deflector head 87 is secured to the ring 85 and hangs over the annular dish 77.

100 The construction is such that materials delivered down through the feed tube 63 on striking the table 71 will pass outward between the vanes 69 and drop thence onto the annular dish. The hood 87 will serve to deflect the materials down onto said dish. The dish is rotated with the table, and therefore, centrifugal force will carry the materials outward in the dish to the upstanding flange which will deflect the same upward into the path of the rising air current in the inner chamber.

110 The dish and hood may be secured to the sleeve 75 referred to, in different positions of adjustment. To accomplish this, the hood ring 85 may have a split or two part ring 88 threaded to a portion 89 of the sleeve 75, the parts of said ring 88 being clamped to said sleeve by bolts 91 entered through lugs 93 projecting outward from the parts of said ring.

115 The construction is such that on release of said bolts the dish and hood may be vertically adjusted with respect to the table and fan as desired, and then may be secured by tightening said bolts.

120 Suitable means may be provided to produce the circulation of air through the inner and outer chambers. This means, in the present instance, is in the form of a fan 95 130

having a hub 96 secured to the upper end of the sleeve 75 and long blades 97 projecting outward from said hub.

Suitable means may be provided for rotating the distributor table, dish and hood, and the sleeve and fan. This means, in the present instance, comprises a hub 101 depending from the table and having a tapered bore fitted on the upper tapered end 103 of a vertical shaft 105 and secured thereto by a screw bolt 107. This vertical shaft has an upper portion journaled in a bearing in a casing 109 and its lower end journaled in an end thrust bearing 111 at the lower end of said casing.

Said vertical shaft may be driven by a bevel gear 113 thereon meshing with a bevel gear 115 on a horizontal shaft 117 journaled in a bearing 119 carried by said casing 109 and in a bearing 121 carried by the foundation ring 1. At the outer end of said horizontal shaft is a pulley 123 adapted to be driven by a belt from any suitable source of power.

The construction is such that the table, dish, hood, sleeve and fan may be readily rotated by means of the simple transmission described. The fan will create a circulation of air through the inner and outer chambers which may flow in the general direction indicated by the tail arrows in Fig. 1.

The fan may be inclosed in a chamber 125 separated from the outer chamber 13 by an annular plate or partition 127 detachably secured by bolts to the outer shell. This plate may have a central opening 129 registering with the upper end of the upper conical shell 29 of the inner casing. The construction is such that the fan will draw the air up through the inner chamber through the opening 129 into the fan chamber.

As stated, one of the purposes of the invention is to provide means for producing a pronounced whirl effect of the air current downward through the outer chamber so as to produce a centrifugal force sufficient to cause the lighter particles to move downward along or adjacent to the inner surface of the outer wall of the outer chamber. To accomplish this, in the present instance, one or more air guides or conduits 131 are provided, in the present instance, two being shown, but the number may be varied according to conditions as desired. Each of these air conduits may be of general helical or spiral form, and may be secured on or adjacent to the outer casing 19 referred to, externally or internally thereof. In the present instance, these conduits are secured to said casing externally thereof, and have upper ends communicating with the fan chamber through inlet openings 133, in the present instance, substantially diametrically opposed, and said conduits have lower outlet openings 135 communicating with the outer

chamber, in the present instance, at substantially diametrically opposed points. The shape of the conduits may vary according to conditions as desired, but in the present instance of the invention, they are of general 70 rectangular cross section and gradually reduced in width progressively downward from their inlet to their outlet openings, with a nozzle effect to increase the velocity and whirl effect of the air current delivered 75 from the conduits.

The construction is such that the air will be forced by the fan outward through the upper inlet openings, thence downward through the conduits through the outlet 80 openings which are so formed as to deliver the air current in relatively thin streams into the outer chamber. These streams will tend to cling to the inner surface of the outer casing 19, and will have a 85 pronounced whirl or helical path of movement which will produce a centrifugal force effect on the particles carried in the whirling air current, and cause said particles to pass downward close to the inner surface of said 90 outer casing. As a result, said particles will be substantially prevented from entrance through the lower opening to be described, between the outer and inner chambers.

It is desirable to vary the strength of the 95 whirling air current delivered by the conduits according to the character of the materials to be separated. To accomplish this, in the present instance, each of the conduit outlet openings 135 may be provided with a gate 100 or valve 137 mounted on a hinge shaft 139 extending upward through the head of the outer casing, where it receives a crank 141 provided with a handle 143 containing a latch 145 (Fig. 4) pressed downward by a 105 coil spring 147, and adapted to coöperate with a series of holes 149 in an arcuate plate 151 mounted on the casing head. The latch has a head 153 on the upper end thereof, the construction being such that the latch head 110 153 may be pulled upward against the resistance of the coil spring 147, and then the handle 143 may be moved over the plate 151 to swing the gate 137 to the position desired, and then the gate may be secured by entrance of the latch 145 into one of the holes 149. Thus, the gate may be set in different positions of adjustment to vary the amount of the outlet opening and the strength of the air current delivered 115 there-through. The gate also serves as a deflector which will contribute to direction of the air current from the outlet opening along the inner surface of the outer casing 19.

The whirling air current on leaving the 125 openings 135 will move downward and thence through the openings 155 back into the inner chamber. Suitable means may be provided to vary the strength of the air current passing through this opening, and 130

to contribute to or promote the whirl of the air current. This means, in the present instance of the invention, comprises a series of valves or deflecting vanes 156, preferably 5 slightly curved, having inner ends pivotally mounted on vertical pins 157 between and secured to angle rings 159 and 161 mounted on the lower conical casing 31 and the collar 51 referred to.

10 To open and close these valves or vanes and hold the same in different positions of adjustment, in the present instance, said valves or vanes are connected by links 163 with arms 165 projecting radially from an 15 adjusting ring 167 mounted on the upper angle ring 159. One of the arms 165^a may be longer than the others and be connected by a rod 169 to a screw 171 threaded in the hub of a hand wheel 173 located externally of the outer casing 19 where it is conveniently accessible. On rotation of the hand wheel the screw 171 will be adjusted in the hand wheel hub, and will thereby adjust the rod 169 longitudinally, and slide or adjust 20 the ring 167 rotatively on the angle ring 159, and said adjusting ring will operate through the links 163 to open and close the valves any extent desired.

These valves or vanes and the adjusting 30 means therefor may be similar to the construction disclosed in my said application Serial No. 319,646.

The direction of said valves or vanes is such that the whirling air current delivered 35 from the conduits will be received by said valves or vanes and deflected thereby from the outer chamber into the inner chamber, and said valves or vanes will desirably contribute to the promotion of the whirl effect 40 of the air produced by the conduits. The outlets 135 for the air conduits are located adjacent to, and in the present instance, a short distance above said valves or vanes, the relation thereof being such that a pronounced whirling effect of the air is produced as it passes downward from the conduit outlets to the opening 155 between the outer and inner chambers. As a consequence, a centrifugal force is produced sufficient 45 to cause the particles carried by the whirling air current to tend to cling to and pass downward along the inner surface of the outer casing 19 remotely from the opening 155 between the outer and inner chambers. As a consequence, the lighter particles are substantially prevented from being carried by the air current back into the inner chamber, and efficient separation of the materials to be graded is accomplished.

60 The head 23 of the outer casing may be provided with a large man-hole 175 detachably secured by clips 177, the construction being such that the man-hole may be removed to permit convenient access to the 65 interior of the casing.

The operation of the separator will be readily understood. The materials are delivered through the hopper 61 and feed tube 63 to the rotary distributor which throws the materials outward and upwardly into the path of the current of air rising in the inner chamber. The lighter particles are carried upward by the air current past the fan through the fan chamber, and thence whirl downward through the conduits into the outer chamber. 70 The lighter particles carried by this whirling air current pass downward, without entering the inner chamber, through the conical casing 49, and are discharged thereby. The heavier particles, on the other hand, 75 gravitate downward through the air current rising in the inner chamber, pass through the collar 51, through the conical casing 57 and are discharged through the spout 59. The general path of the air current is indicated by the tail arrows, and the general paths of the lighter and heavier particles are indicated by the plain arrows in Fig. 1.

80 The adjusting devices for the conduit gates and the adjusting devices for the deflecting vanes at the opening between the outer and inner chambers are located externally of the outer casing of the separator, where they are conveniently accessible for the purpose of setting of said gates or valves 85 or vanes in any position desired, for the purpose of producing the most efficient grading effect.

85 It will be understood that the invention is not limited to the specific embodiment shown, and that various deviations may be made therefrom without departing from the spirit and scope of the appended claims.

90 What is claimed is:—

1. An air separator, comprising in combination, a casing having therein an inner chamber and a divided outer chamber communicating with the inner chamber, a fan in one of the divided outer chambers for circulating the air current up through the inner chamber, means to introduce materials to be graded into the inner chamber in the path of said air current, and spiral guide means leading from the fan containing chamber to the other outer chamber to direct the air current from the fan into the latter chamber while the air current continues its general whirling direction, thereby to produce centrifugal force to throw the particles within the air current outward 110 away from the air entrance to the inner chamber.

115 2. An air separator, comprising in combination, a casing having therein an inner chamber and a divided outer chamber communicating with the inner chamber, a fan in one of the divided outer chambers for circulating the air current up through the inner chamber, means to introduce materials to be graded into the inner chamber in the 120 125 130

- path of said air current, and spiral guiding means for deflecting the whirling air current produced by the fan, laterally to the plane of rotation of the fan into the other outer chamber to whirl about the same, thereby to produce centrifugal force to throw the particles within the air current outward away from the air entrance to the inner chamber.
- 10 3. An air separator, comprising in combination, a casing having therein an inner chamber and a divided outer chamber communicating with the inner chamber, a fan in one of the divided outer chambers for circulating the air current up through the inner chamber, means to introduce materials to be graded into the inner chamber in the path of said air current, and inclined guide means for leading the whirling air current produced by the fan from the fan chamber to the other outer chamber and in a direction laterally to the plane of rotation of the fan, thereby to transfer the whirling current from one divided chamber to the other and to produce centrifugal force to throw the particles within the air current outwardly away from the air entrance to the inner chamber.
- 15 4. An air separator, comprising in combination, a casing having outer and inner chambers therein with an opening between them, a fan for producing an air current traveling in a circuit through said chambers, means to introduce materials into the inner chamber in the path of the air current to be graded thereby, and spiral guide means for conducting the air current from the fan and laterally to its plane of rotation toward the opening between said chambers to promote a whirl of the air current, thereby to produce centrifugal force to throw the particles in the air current outward away from said opening so that they will not enter the opening.
- 20 5. An air separator, comprising in combination, a casing having outer and inner chambers therein with an opening between them, a fan for producing an air current traveling in a circuit through said chambers, means to introduce materials into the inner chamber in the path of the air current to be graded thereby, inclined means for conducting the air current from the fan and laterally to its plane of rotation toward the opening between said chambers to promote a whirl of the air current, thereby to produce centrifugal force to throw the particles in the air current outward away from said opening so that they will not enter the opening, and adjustable means for varying the strength and direction of the air discharged from said inclined means.
- 25 6. An air separator, comprising in combination, a casing having chambers therein, with an opening between said chambers, means for circulating an air current through said chambers, means to introduce materials into one of said chambers in the path of the air current so as to be graded thereby, and inclined conduits progressively reduced from their inlet to their outlet ends for receiving the air current and the lighter particles from one chamber and directing the same with an increasing velocity into the other chamber past said opening a substantial distance from the latter.
- 30 7. An air separator, comprising, in combination, a casing having therein an inner chamber and a divided outer chamber communicating with the inner chamber, a fan for circulating the air current up through said inner chamber, means to introduce materials to be graded into the inner chamber in the path of said air current, said outer chamber having an inlet opening in one divided portion and an outlet opening in the other divided portion, and a spiral conduit extending between and communicating with said openings for receiving the air current and the lighter particles carried thereby, and for directing the same into a portion of the outer chamber.
- 35 8. An air separator, comprising in combination, a casing having therein an inner chamber and a divided outer chamber communicating with the inner chamber, a vertical shaft within the casing, a fan within one of the divided chambers and operated by said shaft to circulate the air current through the chambers, a distributer within the inner chamber and operated by said shaft to introduce the materials to be graded into the path of the air current, and inclined guide means for directing the whirling air current produced by the fan, laterally to the plane of rotation of the fan and into the other divided chamber to whirl about the same, thereby to produce centrifugal force to throw the particles within the air current outward away from the communication between the outer and inner chambers.
- 40 9. An air separator, comprising in combination, a casing having outer and inner chambers therein with an opening between them, means for circulating an air current through said chambers, means to introduce materials to be graded into the inner chamber in the path of said air current, means extending from said air current circulating means toward said opening for promoting a whirl of the air current and lighter particles in their transit from the inner chamber to the outer chamber, and angularly adjustable means for varying the strength and direction of the whirling air currents.
- 45 10. An air separator, comprising in combination, a casing having outer and inner chambers therein with an opening between them, a fan for circulating an air current through said chambers, means to introduce

- 6 materials to be graded into the inner chamber in the path of said air current, an inclined conduit between said fan and opening to receive the air current and the lighter particles carried thereby and conduct the same into said outer chamber, and an adjustable gate for varying the strength and direction of the air current delivered through said conduit.
- 10 11. An air separator, comprising in combination, a casing having outer and inner chambers therein with an opening between them, a fan for circulating an air current through said chambers, means to introduce materials to be graded into the inner chamber in the path of said air current, an inclined conduit between said fan and opening to receive the air current and the lighter particles carried thereby and conduct the same into said outer chamber, an adjustable gate for varying the strength of the air current delivered through said conduit, and a series of vanes at the opening between said chambers for directing the air current from the outer to the inner chamber.
- 15 12. An air separator, comprising, in combination, a casing having outer and inner chambers therein with an opening between them, a fan for circulating an air current through said chambers, means to introduce materials to be graded into the inner chamber in the path of said air current, an inclined conduit between said fan and opening to receive the air current and the lighter particles carried thereby and conduct the same into said outer chamber, an adjustable gate for varying the strength of the air current delivered through said conduit, a series of vanes at the opening between said chambers for directing the air current from the outer to the inner chamber, and means to angularly adjust said vanes further to control the strength of the air current.
- 20 13. An air separator, comprising, in combination, a casing having outer and inner chambers therein with an opening between them, a series of vanes at said opening, a fan for circulating the air current through said opening past said vanes into said inner chamber, spirally disposed guide means for directing the air current from the fan through the outer chamber toward said vanes, and adjustable gate means to vary the strength of the air current for grading materials of varying character.
- 25 14. An air separator, comprising, in combination, a casing having outer and inner chambers therein with an opening between them, a series of vanes at said opening, a fan for circulating the air current through said opening past said vanes into said inner chamber, spirally disposed guide means for directing the air current from the fan through the outer chamber toward said vanes, adjustable means co-operating with said spiral guide means for varying the strength of the air current, and adjustable means for varying the angles of said vanes further to vary the strength of the air current.
- 30 15. An air separator, comprising, in combination, a casing having outer and inner chambers therein with an opening between them, a series of vanes at said opening, a fan for circulating the air current through said opening past said vanes into said inner chamber, spirally disposed guide means for directing the air current from the fan to the outer chamber in the form of a stream traveling circumferentially about the outer chamber, adjustable means co-operating with the spiral guide means for varying the strength and direction of the air current delivered to the outer chamber, and adjustable means for varying the angles of said vanes to vary the direction and amount of air passing through said opening.
- 35 16. An air separator, comprising, in combination, a casing, separating and collecting chambers therein having an opening affording communication between said chambers, a rotary distributor in the separating chamber, means to deliver materials to be graded to the rotary distributor that they may be thrown outward in the separating chamber under the influence of centrifugal force, a fan for causing an air current to circulate through said chambers with upward movement in the separating chamber and downward movement in the collecting chamber, a series of vanes in the opening between the chambers for promoting a whirl of the air passing through the opening, between said vanes, and valve means for regulating the strength of the air current.
- 40 17. An air separator, comprising, in combination, a casing having separating and collecting chambers therein provided with an opening affording communication between said chambers, a rotary distributor in the separating chamber, means to deliver materials to be graded to the rotary distributor that they may be thrown outward thereby in the separating chamber, a fan for causing an air current to circulate through said chambers, adjustable means in the path of the air current returning from the collecting chamber to the separating chamber for promoting a whirl of the air current and varying the strength of the air current thereat, and valve means adjustable further to regulate the strength of the air current.
- 45 18. An air separator, comprising, in combination, a casing provided with separating and collecting chambers having provision to permit an air current to circulate through said chambers with upward movement in the separating chamber and downward movement in the collecting chamber, a fan for creating said air current, means to intro-

- duce materials to be graded into the path of the air moving upward in the separating chamber, valve means in the path of the air current entering the collecting chamber from the separating chamber adjustably to regulate the strength of the air current, and means in the path of the air current returning from the collecting chamber to the separating chamber having provision for promoting whirl of the air current and regulating the strength of the air current.
19. An air separator, comprising, in combination, a casing provided with separating and collecting chambers having provision to allow an air current to circulate through said chambers with upward movement in the separating chamber and downward movement in the collecting chamber, a fan for creating the air current and causing the same to whirl, means to deliver materials to be graded in the path of the upward moving air in the separating chamber, adjustable means in the path of the air current entering the collecting chamber from the separating chamber to regulate the strength of the air current, and adjustable means in the path of the air current returning from the collecting chamber to the separating chamber to regulate the strength of the air current.
20. An air separator, comprising, in combination, a casing provided with separating and collecting chambers having provision to permit an air current to circulate through said chambers with upward movement in the separating chamber and downward movement in the collecting chamber, a fan for creating the air current and causing the same to whirl, means to deliver materials to be graded into the path of the air current moving upward in the separating chamber, means in the path of the air current passing from the separating chamber to the collecting chamber adjustably to regulate the strength of the air current, and means in the path of the air current returning from the collecting chamber to the separating chamber for promoting whirl of the air current.

In testimony whereof, I have signed my name to this specification.

THOMAS J. STURTEVANT.
